UNITED STATES PATENT OFFICE.

EDWIN L. SPRAGUE, OF BOSTON, MASSACHUSETTS.

MANUFACTURE OF BOOTS AND SHOES.

SPECIFICATION forming part of Letters Patent No. 291,796, dated January 8, 1884.

Application filed October 17, 1881. (No model.)

To all whom it may concern:

Be it known that I, EDWIN L. SPRAGUE, of Boston, Suffolk county, State of Massachusetts, have invented an Improvement in the Manufacture of Boots and Shoes, of which the following description, in connection with the accompanying drawings, is a specification.

My invention relates to a novel method of making boots and shoes; and it consists in 10 channeling the inner sole, placing a metallic clinching-surface in the said channel between the main part of the inner sole and the lip of its channel, applying the inner sole to the bottom of the last, drawing the upper over the 15 inner sole, driving the lasting-tacks through the same and into the inner sole opposite the clinching-surface, applying a second or an outer sole to the lasted shoe, driving or inserting metal fastenings through the latter 20 and the upper and into the inner sole against the clinching-surface, which stops or turns the points of the said fastenings, and after the clinching of the fastenings and the removal of the last, removing the clinching-surface, as 25 will be described.

Figure 1 represents in cross-section a shoe made in accordance with my invention, it yet containing the last, but one side of the last is shown as broken away to the better show the 30 clinching-surface in the channel of the inner sole. Fig. 2 is a top view of the inner sole, the channel-flap at one side being removed or lifted to show the clinching-surface, the clinching-surface at the other side of the inner sole being shown in dotted lines.

In the manufacture of my improved shoe, I first channel the inner sole, *a*, in from its edges for seven-eighths of an inch, more or less, forming a channel-flap, *b*, (see Fig. 2,) 40 entirely about it, or entirely about it except at the toe of the inner sole. In this channel I place the clinching-surface *c c*, herein shown as composed of two plates of thin sheet metal, preferably thin sheet-steel about seven-eighths 45 of an inch wide, shaped to fit into the channel, made as shown and described, and to be covered by the channel-flap, as in Fig. 2. The clinching-surface need not be placed in the channel made across the toe of the inner 50 sole, for the foot does not extend into the toe far enough to make the appearance of the fastening through the toe of the inner sole or

its channel-flap objectionable. The clinching-surface is placed in the channel as shown in Fig. 2. The inner sole, *a*, is laid upon the last *d*, the upper *e* is drawn over it and properly secured by lasting-tacks or pegs, and the second or an outer sole or soles, *e'*, laid thereon, has metal fastenings *f* driven through it either from its outer face or in a channel 60 therein, the said nails passing through the outer sole, the upper, and through the main part of the inner sole until the points of the fastenings meet the clinching-surface, when they are clinched or stopped. The usual lasting-tacks are also clinched on the clinching-surface. This clinching-surface is kept close in the channel by the pressure on it of the channel-flap resting against the bottom of the last or the rigid surface within the boot or 70 shoe. The last forms an unyielding resisting surface to support the clinching-surface when the metal fastenings meet it. After the inner sole, upper, and outer sole have been fastened together and the last is out of the boot or shoe, 75 the clinching-surface is withdrawn from under the channel-flap, when the latter, covering the points of the fastenings except at or about the toe, leaves, except at or about the toe, a smooth surface unmarred by nails or 80 fastenings, which hold the outer and inner soles and upper together. By this process it is possible to make a nailed shoe and finish it on the same last without removal, thus saving in cost of lasts and labor of removing lasts, 85 which would not be the case if the clinching-surface were connected with the last.

During the manufacture of the boot or shoe, I retain the channel-flap down in nearly the position it will occupy in the finished shoe, 90 which is a desideratum, and enables the flap to be easily united by any suitable cement with the inner sole after the clinching-surface has been removed.

The clinching-surface *c* may readily be drawn 95 out without greatly displacing the channel-flap.

I claim—

In the art of making boots and shoes, the method of uniting the soles and upper and 100 concealing the lasting-tacks and metal sole-fastenings, which consist in channeling the inner sole, placing a metallic clinching-surface in the said channel between the main part of

the inner sole and the lip of its channel, applying the inner sole to the bottom of the last, drawing the upper over the inner sole, driving the lasting-tacks through the same and 5 into the inner sole opposite the clinching-surface, applying a second or an outer sole to the lasted shoe, driving or inserting metal fastenings through the latter and the upper and into the inner sole against the clinching-surface, 10 to which stops or turns the points of the said

fastenings, and after the clinching of the fastenings and the removal of the last removing the clinching-surface, substantially as described.

In testimony whereof I have signed my name to this specification in the presence of two sub- 15 scribing witnesses.

EDWIN L. SPRAGUE.
